BARBECUE TONGS OR ANALOGOUS ARTICLE

Raymond Spilman, Darien, Conn., assignor to The Washburn Company, Worcester, Mass., a corporation of Massachusetts

Application October 11, 1956, Serial No. 43,318

Term of patent 7 years

(Cl. D44—29)

Fig. 1 is a front view of a barbecue tongs, showing my new design, and

Fig. 2 is a perspective view on a slightly smaller scale of the same article.

The dominant features of my new design are shown in full lines.

I claim:

The ornamental design for a barbecue tongs or analogous article, substantially as shown and described.
